UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ELECTRICAL APPARATUS.

1,330,618.

Specification of Letters Patent. Patented Feb. 10, 1920.

Application filed December 23, 1914. Serial No. 878,791.

To all whom it may concern:

Be it known that I, JOSEPH BIJUR, a citizen of the United States, and residing at New York, in the county of New York and 5 State of New York, have invented a new and Improved Electrical Apparatus, of which the following specification is a full disclosure.

This invention relates with regard to its 10 more specific features, to electrical apparatus for the lighting and starting of automobiles and the like.

One of the objects thereof is to provide 15 simple and practical apparatus of the above nature in which the current is economically used. Another object is to provide a convenient and reliable arrangement whereby the unauthorized use of a car may be prevented. Another object is to provide means 20 in connection with apparatus of this nature whereby injury to the parts is prevented under all conditions of use.

Other objects will be in part obvious from 25 the annexed drawings and in part indicated in connection therewith by the following analysis of this invention.

This invention accordingly consists in the features of construction, combinations of parts, and in the unique relations of the 30 members and in the relative proportioning and disposition thereof; all as more completely outlined herein.

The accompanying drawing, in which is 35 shown one of various possible embodiments of this invention, is a diagrammatic plan.

In this drawing there is indicated at 1 an internal combustion engine connected as by the sprocket chain 2, or other power transmitting device, with dynamo electric apparatus 3. The latter apparatus preferably takes the form of a dynamo electric machine adapted either to turn over the engine to start it or to be driven therefrom as a generator and supply current to the 45 battery, hereinafter referred to.

Leading from one of the brushes of the dynamo 3 is a conductor 4 which has connected therein an electro-magnetic charge indicator 5. This indicator or meter is of 50 a well-known type and in the preferred form merely registers whether the storage battery is being charged, discharged or floating, in accordance with the position of the needle relative to the indices 5^a, 5^b or 55 5^c. This device, the precise construction of

which forms no part of this invention, may be termed a "meter", it being understood that this term is used in a broad sense to comprehend any electro-magnetic indicating or registering device. The conductor 4 60 terminates in a contact block 6 and a conductor 7 leading from the above terminal of the dynamo is connected with a contact block 8, these contacts being preferably arranged along the arc of a circle and separated by an insulating block 9.

Leading from the remaining terminal of the dynamo is a conductor 10 which is connected with one pole of a storage battery 11, the remaining pole of which is connected by a conductor 12 with a movable contact 13 formed upon the arm 14 of a rotary switch pivoted at 15 and actuated as by the thumb-piece 16. The contact 13, in its range of movement, passes from a dead contact 17 over an insulation block 18 and thence successively to the parts 8, 9 and 6. It is to be particularly noted that this movable contact is of such length that in traveling in the above direction it bridges the contacts 8 and 6, as indicated in dotted lines at 19, and thus maintains connection with the conductor 7 until it has made connection with the conductor 4.

The arm 14 is carried past the pivot 15 85 and bears at its opposite end a movable contact 20 which traverses an arc comprising contacts 21 and 22, spaced by the insulating member 23, and also a member 24 which serves to support the contact 20 at its upper range of movement. It may be noted that this range of movement is limited, as by suitable stops 25 and 26, and that there is provided to turn with the switch arm an angular plate 27 having flat surfaces which 95 successively rest against the flattened portion 28 of spring 29 in the positions in which the contact 13 rests upon contact 17, contact 8 and contact 6. In this manner, the switch member tends to occupy one of 100 the above three positions of rest, and if desired a lock device 29^a may be provided to secure it in the "off" position shown in full lines in the drawing.

There is shown at 30 an ordinary mag- 105 neto, the primary circuit of which is completed through the usual interrupter 31 and the secondary circuit of which leads through a distributor 32 and the spark plugs 33. This "magneto", which may indicate any 110

proper source of current, serves to ignite the charges of the engine 1, in the cylinders of which the spark plugs 33 are positioned. A connection to ground from the primary 5 circuit of this magneto leads through contact 21, as indicated at 34, and through a conductor 35 to the contact 22, these contacts being connected by the member 20.

With the parts in the normal "off" position shown, in which they may be locked if desired, the contact 20 bridges contacts 22 and 21, thus short-circuiting the interrupter and rendering the magneto inoperative. In this manner it is assured that the engine 15 cannot run with the switch in the position shown, even if it be cranked by hand, and the car is safe-guarded against unauthorized use. Also, if the switch be opened after the engine is started and circuit thus broken 20 with the battery 11, the system is guarded from an undue rise of voltage by the automatic stopping of the engine.

In the use of this apparatus, when it is desired to start the engine the switch is turned 25 to bring contact 13 into engagement with contact 8. This action breaks the shunt about the interrupter 31 and permits current to flow from the battery 11 through the dynamo 3, undiminished by being forced to 30 traverse the meter 5. In this manner the meter is not subjected to the necessarily large current employed in running the dynamo 3 as a motor to start the engine, and, furthermore, this current is not cut down 35 and wasted. After the engine is started, the switch is turned further until contact 13 comes into engagement with contact 6, interruption of the circuit being prevented as already described. The apparatus now runs 40 in the ordinary way, with the dynamo 3 charging the battery 11, the meter being in use. When it is desired to stop the engine, the switch is merely returned to its normal "off" position, as shown in the drawing.

45 It will thus be seen that there is provided apparatus in which the several objects of this invention are achieved.

As many changes might be made in the 50 above construction, and as many apparently different embodiments might be made of this invention without departing from the scope thereof, it is intended that all features herein described or shown in the accompanying drawings shall be interpreted as illustrative and not in a limiting sense.

Having thus revealed this invention, I claim as new and desire to secure the following combinations of elements, or equivalents thereof, by Letters Patent of the United 60 States:—

1. In apparatus of the class described, in combination, an internal combustion engine, a dynamo electric machine adapted to be driven from said engine or to drive said 65 engine to start it, means connecting said dy-

namo with said engine, a storage battery, an indicator, a conductor leading to said dynamo independently of said indicator, a conductor leading to said dynamo through said indicator, and means adapted to connect 70 said battery successively with said conductors in the above order to start said engine and to charge said battery, said last means being formed to maintain connection with said first conductor until it has made connection with said second conductor. 75

2. In apparatus of the class described, in combination, an internal combustion engine, a storage battery, dynamo electric apparatus connected with said engine, means adapted 80 to connect said battery to said apparatus through one conductor to cause it to turn over and start said engine and through another conductor to receive current from said apparatus after said engine is started, said means being formed to maintain connection with said first conductor until it has made connection with said second conductor, said second conductor being serially connected between said battery and 85 said dynamo electric apparatus, a magneto connected to serve as a source of current for ignition of the charges of said engine, and means adapted to maintain said magneto operative upon said battery being connected 90 to said apparatus and to render it inoperative upon said connection being broken. 95

3. In apparatus of the class described, in combination, an internal combustion engine, a storage battery, dynamo electric apparatus 100 connected with said engine, means adapted to connect said battery to said apparatus through one conductor to cause it to turn over and start said engine and through another conductor to receive current from said 105 apparatus after said engine is started, said means being formed to maintain connection with said first conductor until it has made connection with said second conductor, an indicator connected in said second conductor, a magneto connected to serve as a source of current for ignition of the charges of said dynamo, and means adapted to render said magneto inoperative upon said battery being disconnected from said apparatus. 110 115

4. In apparatus of the class described, in combination, an internal combustion engine, a dynamo electric machine adapted to act as a motor to turn said engine over to start it and to act as a generator when driven 120 from said engine, means connecting said engine with said dynamo, a storage battery, a pair of conductors connected with one terminal of said dynamo, an indicator connected in one of said conductors, a pair of 125 contacts respectively connected with said conductors and spaced one from another, a storage battery one pole of which is connected with the remaining terminal of said dynamo, a movable contact connected with 130

the remaining pole of said battery, a magneto, means connected with said magneto adapted to ignite the charges of said engine, a pair of contacts connected to render 5 said magneto inoperative upon being connected one with the other, a movable contact adapted to short-circuit said last contacts, and a member upon which said two movable contacts are mounted, formed and mounted 10 in such manner that in one position said magneto will be inoperative and said battery disconnected from said dynamo, in the next position said magneto will be operative and

said battery connected directly with said dynamo, and in the third position said magneto will be operative and said battery connected with said dynamo through said indicator. 15

In witness whereof, I hereunto subscribe my name, as attested by the two subscribing 20 witnesses.

JOSEPH BIJUR.
